SERRATED METAL GRATING

Mark M. Stone, Highland Park, Ill., assignor to Metalex Corporation, Libertyville, Ill., a corporation of Illinois

Filed Apr. 21, 1969, Ser. No. 16,835

Term of patent 14 years

Int. Cl. D25—01

U.S. Cl. D13—1

FIG. 1

FIG. 2

FIG. 3 FIG. 4

FIG. 5

FIG. 1 is a perspective view of the grating design of the present invention;

FIG. 2 is an elevational front view of the grating illustrated in FIG. 1;

FIG. 3 is an end view of the grating as viewed from the right-hand side of FIG. 1;

FIG. 4 is a cross-sectional view taken along lines 4—4 of FIG. 1; and

FIG. 5 is an enlarged perspective view of a portion of the grating design of FIG. 1, illustrating in detail the ornamental repetitive pattern thereof.

I claim:

The ornamental design for a serrated metal grating, substantially as shown and described.
